UNITED STATES PATENT OFFICE.

HARRY G. NORWOOD, OF BALTIMORE, MARYLAND.

RAILWAY-RAIL ANCHOR.

Application filed January 31, 1928. Serial No. 250,838.

This invention pertains to an improved one piece rail anchor or anticreeper especially designed to be secured to the base portion of railway track rails and in engagement with stationary parts of the road bed for the purpose of preventing longitudinal displacement of the rails during the travel of the rolling stock thereover.

The main object of the invention is to provide a simple, strong, durable, and economical rail anchor, or anticreeper, which when applied will effectively resist the creeping tendency of the rail.

Another object of the invention is to so construct my improved anchor that any tendency of the rail to creep will oscillate the anchor about its fulcrum against the tie and cause the anchor to more intensely grip the rail.

A further object of the invention is to provide a rail anchor formed of a single piece of sheet metal, such as heat treated steel, which will under all conditions rigidly lock a rail against creeping toward an adjacent tie.

The foregoing and such other objects as may appear from the ensuing description are attained by the construction, arrangement, location and combination of the several parts hereinafter more fully described, illustrated in the accompanying drawings, and particularly pointed out in the claims appended hereto, it being understood that slight changes in the precise form, proportions and minor details of construction may be resorted to without departing from the spirit or sacrificing any of the advantages of the invention.

In the accompanying drawings forming a part of this specification it will be seen that:

Figure 1 is a side elevation of the improved device embodying my invention applied to a track rail, showing the track rail in cross-section and in side elevation a railway tie broken away.

Figure 2 is a plan view of the same.

Figure 3 is a perspective showing the anchor detached from the track rail.

Figure 4 is a side elevation showing the device detached from the track rail.

Figure 5 is an end view looking in the direction of the arrow shown in Fig. 4.

Figure 6 is a cross section taken in the plane of the dotted lines 6—6, Fig. 4.

Figure 7 is a plan view showing the anchor detached from the track rail.

Figure 8 is a side elevation of a slightly modified form of anchor showing the said anchor detached from the track rail, and

Figure 9 is an end elevation of the same, looking from the right hand end of Fig. 8.

In the embodiment of my invention as illustrated it will be seen that the numeral 1 designates a railway track rail and 2 an underlying cross-tie forming a stationary part of the road bed and supporting the rail 1, the said rail having a tendency to creep, when subjected to the strain caused by the travel of the heavy rolling stock thereover.

My improved rail anchor may be formed in any suitable or desirable manner, but is preferably formed from a single piece of (hot pressed) high grade sheet steel of the desired or required length, the solid depending body portion 3 of which is formed with an inwardly concavo-convex portion 4 and an outwardly concavo-convex portion 5, forming a substantially S-shaped depending portion, said concavo-convex portions adding materially to the strength of the anchor, the outer rounded surface of the portion 5 normally resting in contact with the tie throughout the entire length of the anchor, when said anchor has been applied to the track rail, as is clearly shown in Fig. 2 of the drawings. The rounded surface of the portion 5, which rests in contact with the tie, thus prevents the tie from being cut, chipped or otherwise damaged by the forcible engagement therewith of the anticreeping device.

It will be observed that one end of the upright portion 6 of the anchor is provided with a jaw member 7, said jaw member being formed with a laterally extended right angle upwardly inclined flange 8 at its top, and a lower laterally extended upwardly inclined portion 9 below, which latter portion normally rests in contact with the inclined upper surface of the base of the track rail at one side thereof and at the base of the jaw member is formed a laterally extended flange 10 which is adapted to have a clamping contact with the lower face of the rail base, while the opposite end of the anchor is provided with an upright portion 11 which is adapted to snap up,

slightly overlap and clamp the other side of the rail base when the anchor is securely fastened to the rail, and the end portion 11 is provided with a laterally extended flange 12 adapted to have close contact with the edge of the rail base, said flanged portions serving to materially strengthen the formation of the device.

By reference to the slightly modified form 10 of anchor shown in Figs. 8 and 9, it will be seen that the body portion 13 and the jaw end portion 14 are formed substantially as hereinbefore described, while the end portion 15 is formed with an outwardly extended flange 15 16, all of the flanged portions serving to strengthen its formation and to greatly increase its bending resistance.

It will be seen that the lower flanged portion 9 forming a portion of the jaw member 7 20 extends outwardly and is adapted to contact with the upper inclined surface of the rail base, and since these anchors are attached to the rail base by driving the same at its heaviest end until its opposite end snaps into 25 contact with the upper face of the rail base, it will be obvious that as the jaw 7 is forced into its proper position the portion 9 is caused to produce an intense gripping power in contact with the rail.

30 It will be readily perceived that by the construction of anchor hereinbefore described that any tendency of the rail to creep imparts a corresponding tendency to rock the anchor about its fulcrum against the tie. 35 Such tendency of the anchor to rock causes the flanged portions 9 and 10 of the jaw member to more intensely grip the upper and lower surfaces, respectively, of the rail base. Any tendency, therefore, of the rail to creep 40 results in the anchor being more tightly clamped to rail base, and hence more forcibly resists any creeping action thereof.

It will be readily evident that this particular formation of anchor including the 45 plurality of flanges and the body formation are all contributing factors in greatly strengthening the anchor, thus preventing breakage, bending, springing or dislodgment of the anchor when properly applied in position.

50 It will be seen that the contour of the lower or body portion of the anchor is of such particular shape that it avoids contact at depth with the road ballast, thus avoiding

friction and weakening of the anchor by 55 pounding upon the ballast during the passage of the rolling stock thereover.

Having thus described my invention what I claim and desire to secure by Letters Patent is:—

60 1. A single piece rail anchor comprising a sheet of steel formed with a double concavo-convex body portion, a jaw member formed at one end having a top flanged portion and a lower flanged portion, and a clamping portion at its other end.

65 2. A single piece rail anchor comprising a sheet of spring steel formed with an upright and a double concavo-convex depending body portion, a jaw portion at one end formed with a plurality of outwardly extended flanged portions and a clamping portion at its other end.

70 3. A single piece rail anchor comprising a sheet of high grade steel formed with an upright and a double concavo-convex depending body portion, a jaw member having a plurality of laterally extended flanges above the rail base, and a laterally extended flange below the rail base, and a clamping portion 80 at its other end.

75 4. A single piece rail anchor comprising a sheet of steel formed with a depending body portion, said body portion being formed with an upright portion and a substantially 85 S-shaped portion, a jaw member at one end provided with a plurality of laterally extended flanges, and a laterally extended flange, and a clamping portion at its other end.

90 5. A single piece rail anchor comprising a sheet of steel formed with a body portion, said body portion having an upright portion and a substantially S-shaped portion, a jaw member at one end formed with a plurality 95 of extended flanges at one side thereof and an extended flange at its other side, and an upright clamping member at the other end formed with a laterally extended flange.

100 6. A single piece rail anchor comprising a sheet of steel formed with a downwardly extended body portion having a double concavo-convex portion, a jaw member at one end formed with a plurality of extended flanges at one side thereof, and a clamping portion at its other end.

105 HARRY G. NORWOOD.
